ELECTROMAGNETIC CONTROLLER

Arthur M. Cohen, New Rochelle, N. Y., assignor
to Ward Leonard Electric Company, a corpora-
tion of New York

Application December 22, 1944, Serial No. 569,369

5 Claims. (Cl. 200—111)

1

This invention relates to improved electromagnetic controllers adapted for use as regulators for maintaining constant the voltage, or other variable factor, of a dynamo-electric machine.

One object is to provide a compact form of controller which will occupy small space and which is particularly adapted for controlling small units, although it may be utilized for controlling units of large capacity. Another object is to produce an electromagnetic controller of high sensitivity and which is capable of securing close regulation. Another object is to avoid the objections of a vibrating type of controller and to provide regulation by a series of steps which will insure long life and require little or no attention and avoid objectionable sparking and deterioration of the control contacts. Another object is to provide an improved form of structure and relationship of the various parts for securing the above mentioned results, various features of which may be utilized for control purposes other than the particular example herein disclosed. Other objects and advantages will be understood from the following description and accompanying drawings which illustrate a preferred embodiment of the invention.

Fig. 1 is a side view; Fig. 2 is a central vertical section taken at right-angles to the plane of Fig. 1 with the prong socket removed; Fig. 3 is a diagram and bottom view of the prong socket shown in Fig. 1; Fig. 4 is a horizontal section on the line 4—4 of Fig. 2; Fig. 5 is a horizontal section on the line 5—5 of Fig. 2; and Fig. 6 is a side view of the magnetic plunger element, plunger rod and supporting spider and contact spider.

Referring to Figs. 1 and 2, the parts are housed in a cylindrical sheet metal casing 10 of magnetic material having a removable cylindrical cover 11 which is adjustable in an axial direction with reference to the casing 10 for a purpose later explained. This is accomplished by providing inclined slots 11a on opposite sides of the cover through which passes screws 11b having a threaded engagement with the upper portion of the casing 10. It is obvious that by turning the cover or part 11 angularly, the cover will be adjusted axially upwardly or downwardly along the casing 10 and is fixed in any desired position by tightening the screws 11b. The bottom of the casing is closed by a prong base 12 of the radio tube type and is shown as having eight downwardly projecting prongs 12a, as more particularly shown in Fig. 3. This prong base is notched on its circumference at four different portions where portions of the lower edge of the casing 10 are

2

crimped inwardly for retaining the prong base and other parts in fixed position within the casing. The eight prongs of the base are adapted to slide into the openings and engage clips of a prong socket 13 of the type customarily used in radio sets. This is shown in Figs. 1 and 3, being composed of two sheets 13a of insulating material fastened together by a pair of rivets 13b and provided with perforations 13c at opposite ends for supporting the socket and the regulating unit. As shown in Fig. 3, the prong socket is provided with connecting metal strips 14 for providing terminal connections between the prongs 12a and the outside circuit connections. The connectors 14 are provided with portions 14a downwardly extending from the prong socket positioned opposite the openings for receiving the prongs and bent to frictionally engage the prongs when inserted in the socket member. Each portion 14a has extending therefrom a part which passes between the two insulating sheets 13a from which downwardly extend the projections lettered A, B, C, D, E, F, G and H in Fig. 3 for providing connecting terminals to outside devices. The prong base has moulded therewith a downwardly extending central insulated plug 12b having a longitudinally extending key on one side which is adapted to enter a central opening in the prong socket for guiding and correctly positioning the prongs in their engagement with the connectors 14.

Referring to Fig. 2, the magnet coil 15 is shown located within the casing 10 with an intervening cylindrical spacer 16. At the top of the coil is a circular magnetic plate 17 having fastened thereto a downwardly projecting cylindrical central portion 17a also of magnetic material. Below the coil is another circular plate 18 of magnetic material, the casing 10, plate 18 and plate 17 with its portion 17a providing the magnetic circuit to and from the plunger of the magnet. The cylindrical plunger 19 has a central opening through which extends the plunger rod 20. This rod is of reduced diameter in its lower portion over which the plunger 19 fits and impinges against a shoulder on the central portion of the rod. The upper portion of the plunger rod passes freely through the magnetic cylinder 17a and is formed with a shoulder at its upper portion from which a conical portion 20a of the rod extends upwardly. A narrow spacing ring 21 rests on the top of the magnet plate 17 at its outer portion and above this ring is a second similar ring 22. Between these two rings is secured the rim of a spider 23 of quite thin metal, the face view thereof being

shown in Fig. 4. This spider has a central opening through which passes the tapered portion 20a of the plunger rod, the purpose of the spider being to center and yieldably guide the upper end of the plunger rod. As shown in Fig. 4, there extends from the central portion of the spider 23 four radial arms 23a and from one side of the outer end of each arm, a portion 23b extends circumferentially nearly 90°; and their ends extend outwardly to unite with the rim 23c of the spider. The portion which joins the extensions 23b to the rim 23c are each provided with a perforation 23d for the purpose of increasing the flexibility of the interior portion of the spider. The spider is preferably made of steel and tempered to produce a yieldable spring effect. This spider normally tends to hold the plunger rod in its lowest position and serves to slightly oppose the plunger rod in its upward movement and also as a guide therefor. As shown in Fig. 2, the top portion of the cover is indented. A spring 24 of spiral conical form is positioned between the cover and the central portion of the spider 23, the broad base of the spring encircling the indented portion of the cover and the apex of the spring encircling the conical portion 20a of the plunger rod, as shown in Fig. 2. It is apparent that by loosening the screws 11b and rotating the cover 11 the tension of the spring 24 may be adjusted as desired to impose a proper downward force on the plunger rod and plunger.

At the lower end of the plunger is positioned another spider 25 of the same form and character as the spider 23 already described, the spider 25 being particularly shown in Figs. 5 and 6. Against the lower face of the spider 25 is positioned the contact spider 26. This is formed of thin sheet material preferably of coin silver for obtaining good contact with the respective fixed contacts which are engaged thereby. The spider 26 is formed with a central perforated ring portion from which outwardly extend four radial arms 26a shown 90° apart. From the outer ends of these arms and to one side thereof portions 26b extend in a circumferential direction as shown in Fig. 5. The lower end of the plunger rod passes through the spiders 25 and 26 and through a retaining washer 27, the lower end of the plunger rod being peened over the washer for holding the plunger 19 and spiders 25 and 26 in fixed position on the plunger rod.

As shown in Fig. 2, there is positioned between the insulating prong base 12 and the spider 26 a circular plate 28 of insulating material. Two pairs of oppositely disposed rivet pins 29 pass through this insulating plate and through the perforations in the spider 25 and through the lower magnetic plate 18 for securing these parts together. A pair of spacing rings 30 similar to the spacing rings 21 and 22 are located on opposite sides of the rim of the spider 25 for positioning the spiders 25 and 26 in the space between the insulating plate 28 and the bottom magnet plate 18. The parts are all held in position within the casing 10 by the crimping of portions of the lower edge of the casing 10 into notches of the prong base 12 and by circumferentially spaced pins 31 fixed to and projecting from the inside of the casing 10 above the spacing ring 22, as shown in Fig. 2.

In the present instance there are four conducting pins 32 spaced 90° angularly from each other and positioned so that their upper ends come under the ends of the portions 26b of the contact spider 26 as shown in Fig. 2 and particularly in

Fig. 5. These pins are threaded at their upper ends into the insulating plate 28 as shown in Fig. 2. The lower ends of the pins are provided with slots 32a so that they may be adjusted by a small screw driver to correctly position the upper contact ends of the pins with reference to the contact ends of the spider 26. These pins pass within four of the prongs 12a of the prong base and are electrically connected thereto after being correctly adjusted in the insulating plate 28. The four prongs engaged by the conducting pins 32 correspond to the prongs which engage the connectors A, C, E and G of Fig. 3. A resistor 33, preferably in the form of a coiled resistive wire, is connected between the connectors A and C, as shown in Fig. 3; a similar resistor 33a is connected between the connectors C and E; and a similar resistor 33b is connected between the connectors E and G. One terminal of the magnet coil 15 is connected to the prong which engages the connector H and the other terminal thereof is connected to the prong which engages the connector D. A resistor 34 is connected between the connector D and the connector G.

The dynamo-electric machine to be regulated is indicated diagrammatically in Fig. 3 as a direct current generator having an armature 35 and a field winding 36. The load 37 is connected across the outgoing lines of the generator and may be any form of translating device or devices. One terminal of the armature and field winding is connected to the connector H, the remaining terminal of the field winding being connected to the connector A. The remaining terminal of the armature is connected to the connector G. It will be evident that when the regulator is inserted in the prong socket and the spider contacts engage all of the upper contact ends of the pins 32, the circuit of the field winding extends from one side of the armature through the field winding to the connector A to its engaging prong, thence through the contact spider to the prong engaging the connector G to the other side of the armature. When the plunger is in its uppermost position, the contact spider is out of engagement with all of the pins 32 and all of the field resistances will be included in the field circuit, from one side of the armature through the field winding to the connector A, resistor 33, connector C, resistor 33a, connector E, resistor 33b and connector G to the other side of the armature. The magnet coil 15 is connected across the armature through the coil resistor 34 by a circuit from one side of the armature to the connector H, thence through the magnet coil 15, connector D, resistor 34, connector G and to the other side of the armature. The various resistors indicated in Fig. 3 may be located and housed between the prongs of the base and the extending portions of the connectors, thereby securing a compact form of the apparatus.

In the regulating action, the movement of the magnet plunger between its limiting positions is quite small; and the change of current in the magnet coil required for maintaining the voltage constant is likewise quite small. This results in the magnet having high sensitivity and close regulation of the generator output. The spiders 23 and 25 serve to closely guide the movement of the plunger and plunger rod and are sufficiently yieldable so that they do not materially affect the movement of the plunger as controlled by the upward force exerted by the magnet coil and the opposing force exerted by the spring 24. Adjustment of the cover 7 in the manner already described serves to increase or decrease the force

exerted by the spring 24 to any desired degree of refinement; and it is by this adjustment that the voltage of the dynamo-electric machine, or other variable factor, may be set for any desired constant amount.

Regulation is accomplished by control of the field resistors 33, 33a and 33b by including one or more of them in the field circuit as conditions may require. When the plunger is in its lowest position, all of these resistors are excluded from the field circuit because they are all short circuited by the contact spider 26; and when the plunger is in its uppermost position all of these resistors are included in the field circuit resulting in a weakened field. In the intermediate position of the plunger, one or more of these resistors may be included in the field circuit and this is accomplished in the following manner. The radial arms of the contact spider and the extensions therefrom are all in the same plane but the contact ends of the pins 32 are nicely adjusted to lie in different planes; and this difference in adjustment is quite small so that in the range of movement of the plunger and the contact spider, the spider contacts will successively engage the contact heads of the pins 32. Thus the contacting surface of the pin 32 which connects through its prong and socket when the connector G of Fig. 3 is adjusted slightly above the surface of the insulating plate 28; the pin 32 which makes connection with the connector E will have its contact surface adjusted slightly above that connecting with connector G; the pin 32 which connects with the connector C will have its contact surface adjusted slightly above that connected with connector E and the pin 32 which is connected with connector A will have its contact surface adjusted slightly above that of the pin connected with connector C.

When no current is supplied to the magnet winding, the plunger is in its lowest position and the contact extensions of the contact spider are flexed so that all of the pins 32 corresponding to the connectors G, E, C and A are engaged thereby, producing an all-out condition of the field resistors in readiness to produce maximum field strength. During starting, the current in the field winding will gradually build up and thereby gradually increase the current in the magnet coil. When the voltage of the generator exceeds the value for which the regulator is adjusted, the magnet plunger will be raised slightly and first raise the spider contact from the pin 32 which is in connection with the connector G and thereby insert the resistor 33b in the circuit of the field winding; and during running conditions whenever the voltage exceeds the desired constant value, the magnet plunger will rise to cause the contact spider to break connection with one or more of the pins 32 and thereby insert one or more of the resistors in the field circuit for reducing the voltage close to its constant value. When the voltage of the generator falls below the desired constant value, the magnet plunger will move slightly downward and thereby short-circuit one or more of the field resistors by the contact spider engaging one or more of the pins 32. The yieldability of the extensions of the contact spider is so free that they impose a very slight force against the fixed contacts and do not materially affect the position assumed by the plunger as controlled by the current of the magnet coil. In view of the fact that the voltage between terminals of the individual field resistors is comparatively small, the arcing at the contacts of the regulator is slight and in view of the fact that the regulator

changes the connections of the field resistors only when a change of conditions requires it, the sparking at the regulator contacts is infrequent. Also, the spider contacts in making and breaking connection with the pins 32 have a slight wiping action. These conditions serve to avoid deterioration of the contacts and render them durable over long periods of use compared with the usual type of vibrating contact control.

Instead of having contacts of the contact spider in the same plane, the extensions of the spider could be given a permanent set so as to cause the spider contacts to assume positions in different horizontal planes when not in engagement with the fixed contacts and then have the fixed contacts located in the same plane as each other and thereby secure the same regulating effect and control by the movement of the magnetic plunger.

Although a particular embodiment of the invention has been shown and described, it will be understood that various modifications may be made for adaptation to particular requirements and that various features of construction may be embodied in other forms and types of controllers for various uses without departing from the scope of the invention.

I claim:

1. An electromagnetic controller comprising a cylindrical outside casing, a winding within the casing, a plunger rod extending axially within the winding, a magnetic plunger carried by said rod at its lower end, contact means secured to the lower end of said plunger and rod and having a common conducting portion and a plurality of yieldable contact portions extending therefrom angularly disposed about the axis of the magnet, a base of insulating material fixed within and extending across the lower end of the casing, and a plurality of contact elements supported by and extending upwardly through said base and having their inner ends positioned opposite said contact portions respectively within the base and positioned relatively to said contact portions to be successively engaged by said contact portions by the downward movement of the plunger and successively disengaged by the upward movement of the plunger.

2. An electromagnetic controller comprising a cylindrical outside casing, a winding within the casing, a plunger rod extending axially within the winding, a magnetic plunger carried by said rod at its lower end, contact means secured to the lower end of said plunger and rod and having a common conducting portion and a plurality of yieldable contact portions extending therefrom angularly disposed about the axis of the magnet, a base of insulating material fixed within and extending across the lower end of the casing, and a plurality of contact elements supported by and extending upwardly through said base and having their inner ends positioned opposite said contact portions respectively within the base and positioned relatively to said contact portions to be successively engaged by said contact portions by the downward movement of the plunger and successively disengaged by the upward movement of the plunger, said contact elements having a threaded engagement with said base and being individually adjustable towards and from said contact portions.

3. An electromagnetic controller comprising a cylindrical outside casing, a winding within the casing, a plunger rod extending axially within the winding, a magnetic plunger carried by said rod at its lower end, contact means secured to the

lower end of said plunger and rod and having a common conducting portion and a plurality of yieldable contact portions extending therefrom angularly disposed about the axis of the magnet, a base of insulating material fixed within and extending across the lower end of the casing, a plurality of contact elements supported by and extending upwardly through said base and having their inner ends positioned opposite said contact portions respectively within the base and positioned relatively to said contact portions to be successively engaged by said contact portions by the downward movement of the plunger and successively disengaged by the upward movement of the plunger, a cap covering the top of the casing adjustable toward and from the winding; and a spring between the inner side of said cap and the upper end of said plunger rod.

4. An electromagnetic controller comprising a cylindrical outside casing, a winding within the casing, a plunger rod extending axially within the winding, a magnetic plunger carried by said rod at its lower end, contact means secured to the lower end of said plunger and rod and having a common conducting portion and a plurality of yieldable contact portions extending therefrom angularly disposed about the axis of the magnet, a base of insulating material fixed within and extending across the lower end of the casing, a plurality of contact elements supported by and extending upwardly through said base and having their inner ends positioned opposite said contact portions respectively within the base and positioned relatively to said contact portions to be successively engaged by said contact portions by the downward movement of the plunger and successively disengaged by the upward movement of the plunger, and yieldable means at opposite ends respectively of said rod and plunger for guiding their movement, each of said yieldable means comprising a fixed outer circular portion and inwardly extending yieldable supporting portions.

5. An electromagnetic controller comprising a casing, a winding within the casing, a movable

magnetic element within the winding, a plurality of movable contacts opposite one end of the winding carried by said magnetic element, a plate of insulating material secured within the casing opposite said movable contacts, a plurality of fixed contact pins supported by said plate and positioned opposite said movable contacts respectively and individually adjustable in said plate towards and from said movable contacts by threaded engagement with said plate and extending outwardly from said plate and having their inner ends positioned to be successively engaged and successively disengaged during opposite movements respectively of said magnetic element, a base of insulating material secured to the casing opposite and outside said plate, and hollow contact prongs extending outwardly from said base for making external connections, said contact pins extending within and having electrical connection with said prongs respectively.
